CLAIM

The ornamental design for a computer screen with transitional graphical user interface as shown and described.

DESCRIPTION

The patent or application file contains at least one drawing executed in color. Copies of this patent or patent application publication with color drawing(s) will be provided by the Office upon request and payment of the necessary fee.

8. Computer screen with transitional graphical user interface

8.1 : Front

8.2 : Front

8.3 : Front

8.4 : Front

8.5 : Front

8.6 : Front

8.7 : Front

8.8 : Front

The appearance of the transitional image sequentially transitions between the images shown in Figs. 8.1-8.8. The process or period in which one image transitions to another image forms no part of the claimed design.

**1 Claim, 8 Drawing Sheets
(8 of 8 Drawing Sheet(s) Filed in Color)**
